LAMP HAVING HOLLOW TRANSLUCENT
LAMP - SOCKET - SUPPORTING MEM-
BERS CONTAINING TRANSLUCENT
ELECTROLYTE

Henry D. Spence, Plymouth, Mich.

Application May 12, 1948, Serial No. 26,559

7 Claims. (Cl. 240—81)

1

This invention relates to electric lighting fixtures and, in particular, to such fixtures which are supported by uprights such as floor lamps or table lamps.

One object of this invention is to provide an electric lighting fixture having translucent uprights supporting the lamp, these uprights having invisible conductors for conducting the electric current to and from the lamp, so that the conductors are completely concealed.

Another object is to provide an electric lighting fixture of the foregoing character wherein the uprights consist of tubular translucent members containing electrolytes, with electrodes at the top and bottom thereof for leading the current into and out of the electrolyte.

Another object is to provide an electric lighting fixture of the foregoing character wherein the uprights consist of a pair of translucent tubes mounted side by side, or a pair of tubes mounted one within the other, the tubes being of insulating material.

Another object is to provide an electric lighting fixture of the foregoing character which is especially adapted for use with fluorescent lighting tubes, the upright consisting of a hollow walled transparent tube containing an electrolyte which serves as a conductor to transmit current from the base of the lamp to the top of the fluorescent tube.

In the drawings:

Figure 1 is a central vertical section, partly in side elevation, through an electric lighting fixture according to a preferred form of the invention, having transparent uprights with concealed electrical conductors;

Figure 2 is a central vertical section, partly in side elevation, through a modification of the electric lighting fixture shown in Figure 1; and

Figure 3 is a further reduced central vertical section partly in side elevation through a further modification of the electric lighting fixture shown in Figures 1 and 2, and especially adapted for use with fluorescent lighting tubes or other luminous gas-discharge tubes.

Referring to the drawings in detail, Figure 1 shows an electric lighting fixture, generally designated 10, according to a preferred form of the invention, as consisting of a base 11 of any desired shape having recesses 12 and 13 arranged side by side and opening into a central recess 14 which in turn communicates with the outside side wall of the base 11 by means of a bore 15. Inserted in cup-like opaque members 16 seated in the recesses 12 and 13 are two enclosed trans-

lucent tubes 17 and 18 having chambers 19 therein containing an electrolyte 20, such as a solution of sodium chloride in water. Also mounted within the chambers 19 are lower electrodes 21

5 and 22 and upper electrodes 23 and 24. The lower electrodes 21 and 22 are connected by conductors 25 and 26 to terminals 27 and 28 secured to the bridge portion 29 between the recesses 12 and 13 by screws 30. Connected to the terminals 10 27 and 28 are wires 31 and 32 respectively contained in a cable 33 which passes outward through the bore 15 and terminates in the usual connection plug, the prongs of which are connected respectively to the wires 31 and 32. The electrodes 21 to 24 and the conductors 25, 26, 34 and 35 may be of copper or other metal which does not disintegrate easily when immersed in an electrolyte and subjected to the passage of an electric current. The conductors 25, 26, 34 and 20 35 are preferably sealed in the opposite ends of the tubes 17 and 18 so as to prevent leakage of the electrolyte 20.

The upper conductors 34 and 35 lead into an electric light socket or receptacle 38 of any conventional type and containing a conventional incandescent light bulb 39. The socket 38 has the usual knob 40 for actuating the control switch (not shown) by which the electrodes of the socket 38 may be placed into or out of communication with the electric current in the conductors 34 and 35. The electric light socket 38 is provided with the usual threaded stem 41 which is threaded into a bore 42 in a cap 43 mounted on the upper ends of the tubes 17 and 18.

35 For this purpose, the cap 43 is provided with a pair of adjacent recesses 44 and 45 containing opaque cup-like members 46 similar to the members 16 and for a similar purpose. The recesses 44 and 45 open into a cavity 47 in the cap 43 through which the conductors 34 and 35 and wires 36 and 37 pass on their way to the stem 41 of the electric light socket 38.

In the operation of the form of the invention shown in Figure 1, the plug on the end of the cable 33 is plugged into the usual convenience outlet and the switch knob 40 turned to close the circuit. When this is done, current flows, for example, from the wire 31 through the conductor 25 to the lower electrode 21, thence through the electrolyte 20 to the upper electrode 23, conductor 34, into the socket 38 and electric light bulb 39. The current returns by way of the conductor 35, electrode 24, electrolyte 20, electrode 22, conductor 26 and wire 32 to the connection plug. 50 Thus, the current flows through the transparent

electrolyte 29 in both of the uprights 17 and 18 without the necessity for the use of opaque conductors for that purpose. The person looking at the lighting fixture 10 is thus mystified as to the manner in which electricity is conveyed to and from the electric light bulb 39 without the use of copper wires or other opaque conductors running through the tubes 17 and 18. The electrodes 21, 22, 23 and 24 are concealed by the cup-like members 16 and 46.

The modified lighting fixture generally designated 50 shown in Figure 2 consists of a base 51 with a single recess 52 leading into a central cavity 53 and containing a relatively large cup-like opaque member 54. Mounted in the cup-like member 54 is an upright unit or pillar 55 consisting of outer and inner tubular members 56 and 57 containing electrolyte portions 58 and 59 respectively. Mounted in the outer chamber 60 containing the electrolyte portion 58 is an annular electrode 61 which is connected by a conductor 62 passing through the lower end of the outer tube 56 to a terminal 63 in the base cavity 53. Similarly, the lower end of the inner chamber 64 contains an electrode 65 connected to a conductor 66 which passes through the lower end thereof to a terminal 67 likewise mounted in the cavity 53. A cable 33 containing wires 31 and 32 similar to those in Figure 1 is connected to the terminals 63 and 67 and at its outer end carries a similar connection plug (not shown).

The chambers 60 and 64 at their upper ends contain electrodes 71 and 72 similar to the electrodes 61 and 65 and similarly connected to conductors 73 and 74 passing through the upper end of the tube unit 55 into the electric light socket 38 which is of a pattern similar to that of Figure 1 and which has its stem similarly threaded into a bore 77 in the upper end of a hollow cap 78 containing a recess 79 which fits down over a cup-like opaque member 89 which in turn fits over the upper end of the tube unit 55. The light socket 38 is provided with the usual switch knob and also contains a conventional electric light bulb 39.

The operation of the modified lighting fixture 50 shown in Figure 2 is similar to that of the lighting fixture 10 shown in Figure 1, except that current in one direction is conducted through the electrolyte portion 58 in the outer chamber 60, and in the other direction through the electrolyte portion 59 in the inner chamber 64. The modification shown in Figure 2 gives the appearance of a single pillar without any apparent conductors leading to the light socket 75, thereby increasing the mystifying effect upon the observer.

The modified lighting fixture 90 shown in Figure 3 is especially well-adapted for use with a conventional fluorescent lighting tube 91, and for this purpose is provided with a base 92 having a cup-shaped socket 93 into which is fitted the lower end of a hollow-walled tube unit 94 forming the upright or pillar. The tube unit 94 is provided with outer and inner walls 95 and 96 enclosing a chamber 97 containing an electrolyte 98. Annular lower and upper electrodes 99 and 100 and conductors 101 and 102 are mounted in the lower and upper ends respectively of the tube unit 94. The lower conductor 101 is connected to a terminal 103 within the base cavity 104 whereas the upper terminal 102 is engaged by a contact arm 105 which in turn is connected to the upper tube socket 106

for the fluorescent lighting tube 91, the lower socket 107 of which is connected by the conductor 108 to a terminal 109. A cable 33 similar to that of Figures 1 and 2 and similarly containing wires 31 and 32 leads respectively to the terminals 103 and 109, and has a conventional connection plug (not shown), on its outer end for insertion in a convenience outlet. The upper tube socket 106 is mounted in a cavity 113 in a hollow cap 114 which also contains a counterbore 115 into which the upper end of the tube unit 94 fits. In this modification, the side walls of the base 92 and cap 114 extend a sufficient distance along the tube unit 94 to serve as skirts concealing the electrodes 99 and 100.

The operation of the fluorescent lighting fixture 90 shown in Figure 3 is generally similar to that of the fixtures 10 and 50 shown in Figures 1 and 2 respectively. For the types of tube 91 requiring it, the usual ballast (not shown) may be mounted within the base cavity 104. Since the fluorescent tube 91 extends from the bottom to the top of the lighting fixture 90, connection can be made directly to its lower end, hence only a single conductor is required to be run to its upper end. For this reason, only a single electrolyte portion 98 needs to be employed.

All three lighting fixtures 10, 50 and 90 of the invention possess the common feature of providing a substantially invisible electrical connection between the base connections and the lamp socket. The electrolyte, if desired, or the material of the tubes themselves, may be made of any suitable color to increase the beauty of the fixture. As previously stated, the fixture may be of any desired height, so that it may serve either as a table lamp or floor lamp. It is to be understood that the term "translucent" used herein also includes the term "transparent" as the uprights may be of transparent material and possess the same advantages. An opaque conductor in a translucent pillar appears as a vertical shadow even though it may not be clearly seen. The present invention by eliminating such conductors, likewise eliminates the shadows thereof.

What I claim is:

1. An electric lighting fixture for the reception of an electric lamp, comprising a base, a hollow translucent upright rising from said base, said upright having a substantially completely enclosed chamber therein containing a translucent electrolyte extending substantially from the bottom to the top of said upright, spaced electrodes mounted in the upper and lower regions respectively of said electrolyte, a lamp receptacle mounted on said upright and electrically connected to one of said electrodes, all portions of said upright and everything contained in the chamber therein between said spaced upper and lower electrodes including said electrolyte being completely translucent, and a lamp energization circuit connected to said receptacle and including said electrodes with said electrolyte in series therewith, said electrolyte constituting the sole direct electrical conductor between said spaced electrodes.

2. An electric lighting fixture for the reception of an electric lamp, comprising a base, a hollow translucent upright structure having a plurality of substantially completely enclosed chambers therein containing translucent electrolyte portions, spaced electrodes mounted in the upper and lower regions of said electrolyte portions, a lamp receptacle mounted on said upright

structure and electrically connected to the upper region electrodes, all portions of said upright structure and everything contained in the chambers therein between said spaced upper and lower electrodes including said electrolyte portions being completely translucent, and a lamp energization circuit connected to said receptacle, said electrodes being disposed in said circuit in series with said electrolyte portions, said electrolyte portions constituting the sole direct electrical conductors between their respective spaced electrodes.

3. An electric lighting fixture for the reception of an electric lamp, comprising a base, a hollow translucent upright structure having a plurality of chambers therein containing electrolyte portions, a lamp receptacle mounted on said upright structure, and a lamp energization circuit connected to said receptacle in series with said electrolyte portions, said upright structure including a pair of translucent tubular members arranged side by side and containing said electrolyte portions.

4. An electric lighting fixture for the reception of an electric lamp, comprising a base, a hollow translucent upright structure having a plurality of chambers therein containing electrolyte portions, a lamp receptacle mounted on said upright structure, and a lamp energization circuit connected to said receptacle in series with said electrolyte portions, said upright structure including a pair of translucent tubular members arranged one inside the other and containing said electrolyte portions.

5. An electric lighting fixture for the reception of an electric lamp, comprising a base, a hollow translucent upright structure having a plurality of chambers therein containing electrolyte portions and having electrodes mounted in the upper and lower regions thereof, a lamp receptacle mounted on said upright structure, and a lamp energization circuit connected to said

receptacle in series with said electrodes and electrolyte portions, said upright structure including a pair of translucent tubular members arranged side by side and containing said electrodes and electrolyte portions.

6. An electric lighting fixture for the reception of an electric lamp, comprising a base, a hollow translucent upright structure having a plurality of chambers therein containing electrolyte portions and having electrodes mounted in the upper and lower regions thereof, a lamp receptacle mounted on said upright structure, and a lamp energization circuit connected to said receptacle in series with said electrodes and electrolyte portions.

10 15

7. An electric lighting fixture for the reception of a fluorescent lighting tube, comprising a base having a receptacle therein for one end of said tube, a hollow-walled tubular translucent upright rising from said base and having a wall chamber with an electrolyte therein and a central chamber for the reception of said tube, a top member mounted on said upright having a receptacle for the other end of said tube, electrodes mounted in the upper and lower regions of said wall chamber, and a tube energization circuit connected to said receptacle in series with said electrodes and electrolyte.
